CLAIM

The ornament design for a digital video camera with a retractable connector and lens, as shown and described.

DESCRIPTION

FIG. 1 is a front elevational view of a digital video camera with a retractable connector and lens, with the connector in an extended position.

FIG. 2 is a rear elevational view thereof, with the connector in an extended position.

FIG. 3 is a right side elevational view thereof, with the connector in an extended position; and,

FIG. 4 is a bottom plan view thereof, with the connector in an extended position.

The broken lines shown in the drawings illustrate environmental structure and form no part of the claimed design.
